METHOD OF AND APPARATUS FOR
DESUPERHEATINGHenry J. Mastenbrook, Cleveland, Ohio, assignor
to The Swartwout Company, Cleveland, Ohio,
a corporation of Ohio

Application June 13, 1939, Serial No. 278,925

20 Claims. (Cl. 122—479)

This invention relates to desuperheating steam and is more particularly addressed to the problem of efficiently desuperheating under those conditions where the rate of flow of steam is relatively small.

One of the most effective procedures in the art of desuperheating steam, as it is known and practiced today, comprises injecting water into the path of superheated steam under conditions of velocity and/or change of direction with appropriate jets, nozzles, baffles and the like, which will cause the water to be evaporated and transformed into steam, thereby consuming all or part of the superheat or reducing the quality of the steam more or less as may be desired. Obviously, it is desirable and very often imperative that the water which is added to the superheated steam be quickly and efficiently evaporated, so that the desuperheated steam will be of the desired quality and/or reduced degree of superheat as well as free from independent droplets or streams of unevaporated water, all within a limited length of piping, so that a consumer of the desuperheated steam may be certain that raw water will not be contained in the desuperheated steam at the point of use thereof.

A number of satisfactory designs of desuperheaters for the general purposes indicated are known to me, but all of them of necessity are designed on a sufficiently large scale to carry the maximum load expected of them, i. e. the sizes of the steam orifices and passageways, being large enough to permit sufficient flow for maximum requirements, are necessarily such that there comes a point where lesser flows lack sufficient velocity to agitate the water input sufficiently to bring about complete evaporation of the water within the desired or permissible limits of the device. In other words, a desuperheater having sufficient capacity to meet the maximum requirements for which it is designed will tend to have insufficient steam velocity somewhere toward the lower limits of steam flow to function efficiently with respect to atomizing or breaking up and evaporating the cooling water input.

The foregoing assumes, of course, that the water input is efficiently controlled with relation to the steam input and the degree of superheat thereof, so that for normal operating conditions the desired amount of desuperheating is effected. The same control operating in the same way tends to over-supply water at the lower steam velocities with the result that raw water tends to be carried along in the desuperheated steam.

The primary object of my invention is to provide a method and means whereby to extend the lower limits of efficient operation of a desuperheater to embrace the lower velocities of steam flow and the lighter loads to be handled. Other objects include the carrying out of the foregoing objects with simple and economical means; and the provision of an automatic control for bringing my method and means into play at appropriate times, and for and during the conditions of their intended use. Other objects will appear from the following description of preferred embodiments of my invention, reference being had to the accompanying drawings in which:

Figure 1 is a more or less diagrammatic layout of a desuperheating installation in which one form of apparatus embodying the particular features of my invention is shown in relation to the other elements of the system.

Figure 2 is a vertical cross-sectional view of one form of desuperheating chamber having a water inlet in which a form of the instant invention is associated.

Figure 3 is a vertical cross-sectional view showing another form of desuperheating chamber of the Venturi type having a water inlet incorporating a slightly modified form of apparatus embodying the precepts of the instant invention.

Figure 4 shows a further modification of apparatus adapted for use in carrying out the instant invention, more particularly adapted for application to existing installations.

Referring to Figure 1 to show the general environment in which my invention may be practiced, there is disclosed an illustrative desuperheating layout comprising the steam main 1 in which high pressure superheated steam enters at the left as shown at 2, passing through the reducing valve 3 and the desuperheater unit 4, where water is introduced through the pipe 5, after which the desuperheated steam at reduced pressure flows to the right through the main 1, passing within a limited distance of travel, a thermostatic control T, thermometer T', and pressure outlet conduit 6.

In the form of desuperheater illustrated, the thermostat T, by reflecting the temperature of the desuperheated steam, causes a fluid pressure to be raised or lowered in a conduit 7, which in turn controls the movement of a valve 8 in the water line 5, whereby to increase or decrease the flow of water to give the desired resulting temperature to the desuperheated steam. It will,

of course, be appreciated that, if the desuperheated steam passing the thermostat T is not homogeneous, i. e. free from drops of raw water or free from streams of raw water, the desired results will not be obtainable. Hence the function of the main desuperheater 4 is essentially to bring about the intimate mixing of the steam and water and to so enhance the ultimate evaporation of the water in a limited length of time, and perhaps also a limited travel in the low-pressure steam main, that the whole function of evaporating and mixing the water and steam will be accomplished before the steam passes the thermostat T. The control of the reducing valve is appropriately managed by the imposition of steam pressure through the conduit 6 on a master control M, which controls the reducing valve 3. All the foregoing is, of course, illustrative of that which is practiced in the art prior to my invention.

The desuperheater housing or mixing chamber 4 may conveniently take the form illustrated in Figure 2 in which the incoming steam is diverted downwardly through a tapering conduit through a reduced orifice 10, thereby passing the water jet or nozzle 11. The steam is given an increasing velocity toward and through the restricted orifice 10, and is then caused to reverse its flow through 180° to the outlet orifice 12. The lower portion of the body of the desuperheater 4 may be tapped off to a steam trap 9, see Figure 1, so that excess water will not accumulate in the bottom of the desuperheater housing.

Considering particularly Figures 1 and 2, it will be appreciated that as the load on the whole installation is reduced, there will come a point where the velocity through the desuperheater 4 is so low that the velocity through the orifice 10 and adjacent the water jet 11, and elsewhere in the device, will be incapable of giving sufficient mechanical atomization or agitation to the water to bring about enough evaporation thereof to accomplish the desired desuperheating. The result of such low load operation may be that the water will either accumulate in the bottom of the desuperheater or be carried along in drops or streams in the low pressure main.

To correct this situation my invention provides the introduction of steam into the water line through such means as the branch conduit 13, shown in Figure 1 as leading from the high pressure side through appropriate control valves 14 and 15, to the water main 5 as at 16. Referring particularly to Figure 2 the high pressure steam enters the housing 16 through which the water line 5 passes, and the water line 5 is so constructed as to provide within the housing 16 a substantially annular and inclined orifice 17, through which the steam may enter the water conduit 5 and pass along with the water therein through the jet 11 into the inflowing steam in the body of the desuperheater 4. Although I have shown steam being led from the particular point in the high pressure line indicated in Figure 1, it is, of course, only essential that steam be introduced through the orifice 17 at a higher pressure than the water pressure in the pipe 5 and the source of steam supply is immaterial.

The operation which results is that when the load on the desuperheater is small, the flow of both steam and water is small, hence the flow of water through the pipe 5 is relatively slow or sluggish. With, however, the introduction of steam through the orifice 17, the mixed fluid con-

tent of steam and water in the pipe 5 between the orifice 17 and the jet 11 is greatly increased in volume, and hence greatly increased in velocity. Thus the velocity of the mixture emanating from the jet 11 is increased so that the relative speed relationship of the drops or streams of raw water with respect to the adjacent steam in and around the jet 11 and the orifice 10 in the desuperheater is raised to a point where mechanical atomization and spreading of the liquid particles is enhanced to facilitate greatly the evaporation of the water. In like manner, where the flow of water through the pipe 5 is still less, the flow of steam beginning at the orifice 17 may be as high as desired, i. e. high enough in its flow, particularly through the orifice 17 and the remaining portion of the water pipe 5 and out through the jet 11, so that, within this length of the pipe 5 the mechanical breaking up and mixing of the water may be largely, if not wholly, accomplished. This results in a wet steam or mist being forced through the jet 11 into the adjacent superheated steam and the relatively slowly moving superheated steam is not called upon to perform the function of atomizing or mechanically breaking up raw water. In this manner the superheated steam is desuperheated by the addition to it of wet steam from the jet 11 or a mixture of wet steam and water vapor or mist or the like, as distinguished from the ordinary injection of raw water into the superheated steam.

I have found it feasible to control the flow of steam into the water line by such a simple means as a hand valve (not shown) set to give sufficient steam flow through the pipe 13 for the minimum desired output of desuperheated steam, and then permitting this quantity of high pressure steam to flow into the water pipe 5 throughout all periods of greater load, since under the conditions of greater load and greater flow of water through the pipe 5, the addition of the relatively small amount of steam has little effect except perhaps to warm the water somewhat in its flow from the orifice 17 to the jet 11. Where high pressure superheated steam is thus introduced into the pipe 5, there is no loss of efficiency of the device as a whole, because the gross result is that the same ultimate amount of superheated steam is ultimately desuperheated and the same amount of water added thereto. Where only a hand valve is used to control the input of the high pressure steam to the water line, the operator must, of course, shut the hand valve when the device is put out of operation.

To make the whole operation automatic, I provide as shown in Figure 1 a pair of valves 14 and 15 in the high pressure auxiliary steam line 13, which may conveniently be controlled by the same source of pressure that controls the reducing valve 3. Thus where I have shown a reducing valve 3 to be opened in response to increasing control pressures in the diaphragm chamber thereof, I provide that the valve 14 be similarly arranged and that the valve 15 be oppositely arranged. Each of the valves 3, 14 and 15 may appropriately have adjustable springs S operating on the valve stems, tending to close the valves 3 and 14 and tending to open the valve 15 as against the actuating pressure imposed upon the diaphragms thereof from the master control M. When the load on the whole system is normal or high, the pressure from the master control will of course be high enough to hold the reducing valve 3 in a well opened position, and the same pressure will hold the valve 14 well opened, but

will shut or tend to shut the valve 15 whereby to shut off the flow of steam through the auxiliary line 13, thus permitting the whole installation to work in the manner known prior to my invention. As, however, the load on the whole installation decreases and the steam velocity in the pipe 1 begins to get down to the point where my invention comes into play, the pressure from the master control M will necessarily become less, permitting the spring S to throttle the reducing valve 3 and open the valve 15. The springs in the valve 14 are then appropriately adjusted, so that the valve 14 stays open, permitting steam to flow through the auxiliary line 13 into the mixer 16, through the orifice 17 into the water line 5, where it performs the function of increasing the velocity from the orifice 17 to the jet 11 and vaporizing, agitating or evaporating the water therein prior to its introduction into the desuperheater 4 as above described.

The springs S in the valves 3 and 14 are so set, however, that whenever the valve 3 closes the valve 14 will thereupon also close, whereby to shut off all flow of steam from the high pressure side. When this occurs the temperature in the low pressure side of pipe 1 will fall to a point where the thermostat T will also shut off the water valve W, and the system will automatically have come to rest, the whole shutting down sequence being initiated by a reduction in consumption of steam at the point of consumption beyond the low pressure end of line 1 in the apparatus illustrated in Figure 1.

From my prior observations, it will also be understood that the automatic operation above described may profitably be carried out without the use of the valve 15, since the additional flow of steam through the line 13 and into the desuperheater 4 through the water line 5 will, in substantially all instances, have no deleterious effect at high or normal loads.

The adaptability of my invention to a Venturi type of desuperheater is shown in Figure 3, the auxiliary high pressure steam being led into the water system through the steam inlet 20, the water being introduced under suitable control to the inlet 21, and flowing through the conduit 22-23 to the jet 24 in the Venturi throat V, where the steam, flowing as shown by the arrow, passes the jet. The restricted orifice 25 receives the water from the jet 24 under normal loads and evaporates and atomizes the same at the point of high velocity adjacent the orifice 25. In this form, the auxiliary steam enters through the inlet 20 into the chamber 26 surrounding the conduit 22, and passes into the water conduit 23 through the confined annular orifice 27, thereafter functioning in its effect upon and with the incoming water as above described.

The details of construction which I have found advantageous are illustrated in one desirable form in Figure 3, in which the chamber 26 is shown to be formed in a flanged housing 30 into which is preferably internally threaded the conduit 22, the lower end of which, as shown, is externally chamfered, preferably about at the angle shown, whereby to lie a spaced distance from the internally chamfered end of the conduit 23. The conduit 23 in turn is preferably grooved as at 31, and brazed or welded to the collar 32, which is clamped between the flanges 30 and 33 by bolts 33', thereby also closing the extension of the Venturi chamber through which the water conduit 23 enters. By this construction any desired size and shape of the orifice 27

may be obtained by the removal of the upper flanged housing 30 and the substitution of longer or shorter conduits 22 with varying degrees of chamfer to give the character to the orifice 27 that is found most appropriate in use. The annular inclined configuration of the orifice 27 has been found by me to be practical and efficient, particularly in that the inflowing high pressure steam tends to tear away water that is flowing along the walls of the conduit 22 directly above the orifice and to agitate this water very vigorously in its passage in the mixture of fluids between the orifice 27 and the jet 24.

Referring back to Figure 2, it will be seen that 15 the details of construction of the jet are modified slightly in that the water conduit 5 is brazed or welded directly to the housing 16, terminating in an externally chamfered end in the central portion thereof adjacent the orifice 17, and that 20 a separate length of pipe or conduit 5' is separately brazed or welded to the lower portion of the housing 16, having its upper end internally chamfered and spaced from the externally chamfered end of the pipe 5. The lower portion 25 of the pipe 5' is shown to be externally threaded into the adjacent flange through which the whole assembly is bolted with the other appropriate elements of the flange joint on the top of the desuperheater body 4 as shown.

30 In Figure 4 a further modification of the details of an alternative form of mixer construction is illustrated. This form may be particularly convenient for use with existing installations and comprises essentially a standard pipe T at 40 in the upper end of which the incoming water may flow in a pipe 41, which has its lower end externally chamfered at 42. The pipe 41 may conveniently be threaded into the T as shown and brazed or welded in a selected position as seen at 43. Similarly, the outflowing connection may comprise the pipe 44, internally chamfered at 45, threaded into the lower connection of the T and brazed or welded at 46 in the desired position, whereby to give an inclined annular orifice 47 of the size desired. In assembling the parts the size of the orifice 47 may be observed through the middle opening 50 of the T prior to the welding of one or both of the welded joints 43 and 46. The steam line may thereafter be connected to the opening 50 as shown, whereby the annular steam chamber 51 will surround the orifice 47. In this form I have shown an internal restriction 48 in the pipe 41 immediately preceding the orifice 47, whereby to increase the water velocity at this point as well as to concentrate the water stream and subject it to an extra mechanical agitation from the steam entering the orifice 41 adjacent thereto. The whole assembly just described may be appropriately joined to the body of the desuperheater by threaded engagement with an appropriate flange joint attached to the water or fluid conduit 49 which may continue in the manner of the conduit 23 shown in Figure 3, or otherwise embrace 55 a sufficient length of conduit to permit the agitation of the fluid therein prior to its delivery to the body of the desuperheater for the purposes above described.

70 While I have referred to that portion of the apparatus in which I introduced the high pressure steam to the water of the desuperheater as a mixer, I use the term only for convenience here without seeking to add or detract from the functions it performs. Although I have described a 75 preferred form and one or two modifications

thereof, and have illustrated a practical embodiment of means through which my invention may be practiced, various modifications and changes thereof will occur to those skilled in the art without departing from the precepts of my invention, and I do not care to be limited to the particular forms herein illustrated and described or in any manner other than by the claims appended here-to when construed to have that range of equivalents to which they are entitled in view of the state of the prior art.

I claim:

1. The method of desuperheating steam which includes the steps of adding, to flowing superheated steam, water in amounts controlled with respect to the character of desuperheated steam, and mixing with the water, prior to its meeting the superheated steam, an increasing quantity of steam as the flow of superheated steam decreases.

2. The method of desuperheating steam which includes the steps of adding, to superheated steam, water in amounts controlled with respect to the character of desuperheated steam and increasing the temperature of such water as the rate of flow of superheated steam decreases, such temperature increases being effected prior to adding said water to said superheated steam.

3. The method of desuperheating steam which includes the steps of adding water to flowing steam to be desuperheated when the flow of said steam exceeds a predetermined amount, and adding a mixture of water and steam to the steam to be desuperheated when the flow of said steam becomes less than said predetermined amount.

4. The method of desuperheating steam which consists in reducing the pressure of one part of the superheated steam, supplying water thereto, injecting said water into said steam with another part of said superheated steam at a greater pressure than said reduced pressure, and varying the amount of said other part of said superheated steam in inverse proportion to the pressure of the de-superheated steam.

5. Desuperheating apparatus of the type described including a desuperheater unit having a steam inlet and a steam outlet, a conduit extending into said unit and having a discharge outlet disposed in the path of steam flowing through said desuperheater unit, means for supplying water to said conduit, and means for injecting steam into said conduit comprising an opening extending through the wall of said conduit and spaced from the discharge end thereof, walls defining a chamber around said opening and a conduit connecting said chamber to a source of supply of steam under pressure.

6. A desuperheater comprising a casing having a steam inlet and a steam outlet, a conduit extending in 'o said casing and having a discharge outlet therein between said steam inlet and steam outlet, and walls defining a steam chamber surrounding a section of said conduit and having a steam inlet opening into said chamber, said section of said conduit having an opening in the wall thereof whereby steam from said steam chamber may enter said conduit.

7. A desuperheater comprising a casing having a steam inlet and a steam outlet, a conduit extending into said casing and having a discharge outlet therein between said steam inlet and steam outlet, and walls defining a steam chamber surrounding a section of said conduit and having a steam inlet opening into said chamber, said sec-

tion of said conduit including spaced beveled end portions forming an annular inclined steam inlet opening through the wall of said conduit.

8. The method of de-superheating steam which consists in reducing the pressure of one part of the superheated steam, supplying water thereto, injecting said water into said steam with another part of said superheated steam at a greater pressure than said reduced pressure, and throttling said other part of said superheated steam when the flow of said one part of said superheated steam exceeds a predetermined amount.

15 9. The method of de-superheating steam which consists in reducing the pressure of one part of the superheated steam, supplying water thereto, injecting said water into said steam with another part of said superheated steam at a greater pressure than said reduced pressure, and throttling the flow of said other part of said superheated steam when the flow of desuperheated steam reaches a predetermined minimum.

20 10. The method of desuperheating superheated steam which consists in dividing the flow thereof into two separate parallel paths, throttling the flow in one path to maintain a desired aggregate flow through both paths while maintained a higher velocity flow in the other path at least when the said desired aggregate flow is small, adding water to the steam flowing at the higher velocity in said other path in amounts sufficient to bring about the desired amount of desuperheating of the aggregate contents of both paths, causing said water and steam to contact in an initial mixing zone and then flow together in a part of said other path which is long relative to said zone and mix and commingle therein while tending to over-desuperheat the steam therein, and thereafter joining said paths and mixing the said mixture and/or over-desuperheated steam from the second path with the superheated steam flowing from the first path.

25 11. The method of desuperheating superheated steam which consists in dividing the flow thereof into two separate parallel paths, throttling the flow in one path to maintain a desired aggregate flow through both paths while maintaining a higher velocity flow in the other path at least when the said desired aggregate flow is small, adding water to the steam flowing at the higher velocity in said other path in amounts sufficient to bring about the desired amount of desuperheating of the aggregate contents of both paths, causing said water and steam to flow together in said other path and mix and commingle therein while tending to over-desuperheat the steam therein, and thereafter increasing the velocity of the whole fluid contents of the second path and projecting the same at said increased velocity into said first path.

30 12. The method of claim 11 which includes the further step of causing the velocity of flow of superheated steam in said first path to increase where it receives the contents of said second path whereby to facilitate the mixing of the aggregate contents of both paths and the transfer of heat from the hotter to the cooler parts thereof.

35 13. The method of desuperheating superheated steam which is flowing in the first of two separate parallel paths which consists in causing steam to flow in the second path, throttling the flow in said first path to maintain a desired aggregate flow through both paths while maintaining a higher velocity in the second path at least when the said desired aggregate flow is

small, adding water to the steam flowing at the higher velocity in said second path in amounts sufficient to bring about the desired amount of desuperheating of the aggregate contents of both paths, causing said water and steam to contact in an initial mixing zone and then flow together in a part of said second path which is long relative to said zone and to mix and commingle therein while tending to wet the steam and vaporize the water therein, and thereafter joining said paths and mixing the contents thereof.

14. The method of claim 13 which also includes the step of increasing the velocity of the whole fluid mass flowing in said second path when it joins the first path and projecting said mass at said increased velocity into the superheated steam flowing in said first path.

15. The method of claim 13 in which said second path is restricted in area adjacent the point where water is added thereto and thereby accelerating the movement of steam where the water is first added to it to break up the water particles preliminary to the mixing thereof with the steam in said second path.

16. The method of desuperheating superheated steam which consists in moving superheated steam in a confined space past a nozzle from which desuperheating fluid is introduced to the superheated steam, introducing water in amounts controlled with respect to the condition of desuperheated steam into a second confined space separated from said first space which communicates therewith only through said nozzle, introducing steam into said second space in amounts which maintain an atomizing velocity through said nozzle at least when the rate of water input would be too small to cause substantial atomization at said nozzle if flowing therethrough alone, mixing said steam and water in said second space to form a desuperheating fluid, and ejecting said fluid through said nozzle with an accompanying drop in pressure of said fluid into the superheated steam in said first space.

17. A desuperheater having an inlet for superheated steam, an outlet for desuperheated steam, and a water inlet conduit terminating in the desuperheater in a restricted discharge orifice disposed in the path of superheated steam, means responsive to the condition of desuperheated steam for feeding water into said conduit at rates sufficient to maintain the desired condition of desuperheat, and means for feeding steam into said conduit at a point spaced away from and ahead of said orifice at pressures in excess of the pressure in said desuperheater and in amounts which tend to agitate and accelerate the movement of water from said point to said orifice at least when the rate of water input is small, the portion of said conduit between said point

and said orifice comprising a mixing chamber permitting said water and steam to form a substantially homogeneous desuperheating fluid mass having characteristics of wet steam, said restricted orifice projecting said desuperheating fluid into the superheated steam at a substantially higher velocity than would be the velocity of the water alone when the rate of water input is small.

18. In combination a desuperheater having a superheated steam inlet, a desuperheated steam outlet and a water inlet conduit with a discharge orifice disposed in said desuperheater, a reducing valve in said steam inlet, a steam conduit leading from said steam inlet ahead of said reducing valve to said water inlet conduit at a point ahead of said discharge orifice, means controlling the supply of water responsive to the condition of desuperheated steam for increasing the flow of water when the amount of desuperheating is less than desired, and means including said reducing valve for maintaining a reduced pressure in said desuperheater compared with superheated steam pressure ahead of said valve whereby to force steam through said steam and water conduits, the portion of said water conduit between said point and said orifice comprising a chamber communicating with said desuperheater only through said orifice in which steam and water are mixed and fluid pressure is maintained to cause higher velocity through said orifice than would result from the flow of water alone at least when the amount of water required for desuperheating is small.

19. The combination of a desuperheater having a steam inlet, a water inlet and a steam outlet, a conduit leading from a supply of water under pressure to said water inlet, valve means responsive to outlet steam pressure for restricting the flow of steam through said steam inlet when the outlet steam pressure exceeds a predetermined amount, valve means in said conduit responsive to outlet steam temperature controlling the flow of water through said water conduit and increasing the water flow as outlet steam temperature tends to exceed a predetermined value, a steam conduit leading to said water conduit between said water valve means and said water inlet, and valve means in said steam conduit responsive to outlet steam pressure for restricting the flow of steam therethrough when the outlet steam pressure exceeds a predetermined amount.

20. The combination of claim 19 with valve means in said steam conduit responsive to outlet steam pressure for restricting the flow therethrough when the outlet steam pressure becomes less than a different predetermined amount.

HENRY J. MASTENBROOK.
